UNITED STATES PATENT OFFICE

2,646,863

FASTENER DEVICE

Henry E. Hinz, Forest Park, and Henry C. Fletcher, Wooddale, Ill., assignors to Admiral Corporation, Chicago, Ill., a corporation of Delaware

Application April 17, 1950, Serial No. 156,348

2 Claims. (Cl. 189—78)

1

This invention relates to a fastener, for retaining two parts in association with each other, one of the parts extending through or around the other part.

In greater detail, the fastener comprehends a simplified fastening device which may take the form of a single piece of material such as steel of a resilient quality which is bent to a formation in which it may be employed for retaining a window frame in association with an opening in a wall, such as a window frame of the class employed in the front of a cabinet for a television and/or a radio receiving set.

Of various media which have been employed for attaching windows, including their frames, to the casing of cabinets at openings therein through which a television picture or a dial is viewed, none has been without defects for assembly line manufacture, especially when the window is of a plastic material and is an integral part of the frame. For example, fasteners of one class are too expensive insofar as their first cost is concerned. Other fasteners cannot be assembled quickly enough. And still others are unsuitable for use with comparatively soft plastic material of the window frames and their use is frequently followed by fracture or deformation of the plastic parts.

Because of the present invention, a fastener may now be provided which obviates the foregoing disadvantages since the fastener is inexpensive of manufacture, may be produced from inexpensive material and which calls for no special skill in its application.

Other advantages of the invention, as well as the invention itself, will become apparent from the following description of embodiments thereof, which description is illustrated by the accompanying drawings and forms a part of this specification.

In the drawings:

Fig. 1 is a fragmentary sectional view taken on line 1—1 of Fig. 4, the fastener being in completely assembled relationship to the other parts;

Fig. 2 is a sectional view, corresponding to Fig. 1, showing the fastener in the process of being assembled with the frame;

Fig. 3 is a perspective view of the fastener;

Fig. 4 is a fragmentary elevational view from the right hand side of the parts shown in Fig. 1;

Fig. 5 is a sectional view taken on line 5—5 of Fig. 4;

Fig. 6 is a perspective view of a second embodiment of the fastener; and

Fig. 7 is a perspective view of a third embodiment of the invention.

2

In Fig. 1, wherein for the purpose of illustration is shown one embodiment of the invention, the reference character 8 is used to denote one of the walls of a cabinet which is formed with an opening 9. In association with the opening is a combined window frame and window 11 which is made of transparent molded plastic material. The frame 11 is ornamenteally masked adjacent its edge portions only, to provide a window portion 12 centrally of the frame, through which an object such as a television picture tube or dial of a radio receiving set within the cabinet may be viewed. A flange portion 13, which extends over the external surface of the cabinet from opening 9, limits displacement of the frame to the right (Fig. 1), and displacement thereof transversely of the axis of said opening is precluded by intimacy of association of a rim portion 14 with that portion of the cabinet defining the opening 9. The rim 14 extends to an edge thereof 16, adjacent the rear extremity of opening 9, and is formed with lugs 17, any number of which may be present on the edge and which are preferably integral with the window frame 11. Each of the lugs 17 is apertured by a slot 18 to provide a seat or pocket for a purpose later to be described. These seats may also be provided by recesses molded or cut in the lugs, or may be provided by means of other members, having seats thereon, molded in the lugs.

A novel clip or fastener 19 is adapted to cooperate with each of the seats for anchorage of the clip to the frame 11, and concurrently, for securing the frame to the cabinet. For a clearer understanding of the operation of this device, reference should be made to Fig. 3 wherein the fastener is shown as a single piece of substantially resilient wire bent to the conformation shown.

As will be noted, the fastener includes at least one hook or intermediate portion 21 which is between and offset from the ends of a pair of inner parallel arms 22 bent at the ends to continue laterally away from each other to outer parallel arms 23. Each of the pair of arms 22 provide, with arms 23, a wing portion 24 adapted to engage the inner surface of the rim 14 while the hook portion 21 extends into the slots 18. Desirably, of course, the arms 22 are only slightly closer to each other than the length of the slot 18, so that when in association with frame 11, the fastener is anchored against displacement along the edge 16. Also, when in association with frame 11, a saddle portion 26 on each side provided by an upward continuation from each of the arms 23, is in intimate association with the edge 16. The hook portions 21 are further

adapted to be retained in engagement with the seats 18 by offset portions 27 of the saddle 26 which extend toward each other in parallel spaced relation from the plane of the wing portions 24. The spacing of these offsets from the plane of the wings is such that the hook portion 21 is resiliently held in the slot 18 by engagement of the offsets 27 with the upper surface of the lug 17. The offset portions 27 are additionally biased toward the lugs 17 by deflection of a pair of arms 28, in extension upwardly from the offset portions 27 and which collectively provide a third wing portion.

Assembly of the parts as indicated in Fig. 1 is carried out by sliding the rim 14 through opening 9 as far as flange 13 will permit. The fastener 19 is then slid over the lug 17, the hook portion 21 being forced away from the offset portions 27 to enable said hook portions to clear the extremities of the lugs thereby pinched between portions 21 and 27 (Fig. 2). At the same time, that the saddle portions are moved into engagement with the edge 16, the hook portion 21 is carried over the slot 18 into which the hook snaps.

As was previously indicated, the wing portions 24 and 23 are deflected while in operation. This is because the process of assembling the clip 19 with the wall 8 and frame 11 involves spreading of the wing portions 24 and 23 angularly with respect to each other. This operation does not involve bending any portion of the clip beyond its limit of elasticity, however. The wall 8 is consequently squeezed between wing portions 28 and the flange 13.

An explanation of the method and means by which the window frame may be assembled into the cabinet 8 having been set forth, the factor of time saved by use of the novel clip will be apparent. But there is an additional factor which is advantageous to assembly of the foregoing parts, particularly when the parts are assembled by mass production methods. That is the safety factor, the significance of which can best be understood from Fig. 1. Therein, the character 47 is used to denote the screen portion of a cathode ray tube. If such a tube were to be mounted on its chassis protruding towards the front of the cabinet too far, it might, when the chassis was assembled into the cabinet, strike the inside of the window frame 11, tending thus to unseat the flange 13 as indicated by the broken lines in Fig. 1. Use of the clips embodying the present invention, however, will prevent breaking of any parts, however, because the resilience of the clip will allow a certain amount of movement of the window resisted only by the resilience of the clips.

While the construction indicated in Fig. 3 includes arms 28 terminating free ends and the hook portion 21 is at the middle of the strip of wire from which the fastener is constructed, as a preferred construction, a fastener in which the hook portions are at the free ends is also contemplated. Such a construction is shown in Fig. 6

wherein a third wing portion 31 is formed from the middle of the blank section while the ends of the blank are bent to provide hooks 32 adapted to be operatively engaged by the slot 18.

A third embodiment of the invention is also contemplated. This construction takes the form of a blank struck from sheet metal and also bent to include a wing portion 41, adapted to engage the inner surface of the rim 14, and a wing 42 adapted to engage the wall 8. The function of the saddle portions 26 including the offsets 27 is performed in this embodiment by a bridging saddle part 43 which also embraces the lug 17 when in place. A hook portion 44 extends upward from the body 46 of the lower wing member 41 in the same manner as in prior described embodiments, and serves the same purpose.

Having thus described our invention in three embodiments thereof, we are aware that numerous and extensive departures may be made therefrom without departing from the spirit or scope of our invention.

We claim:

1. In a wall formed to provide an opening therein; window means having a rim extending through said opening and flange means extending from said rim engaging said wall adjacent said opening, said rim being formed with clip engaging lugs, said lugs including a seat formed therein, and resilient clip means engaging each of said lugs, each comprising at least one resilient wing means engaging said wall on the side opposite to said flange, said wing means being formed with offset arms extending on both sides of said lug, at least one other wing means extending from said arms engaging said rim on one side, said arms being formed to engage the other side of said rim at said lug, said other wing means including a seat engaging means engaged in said seat to hold said clip means in place.
2. In a window assembly having a wall formed with an opening therein, window means disposed in said opening including a flange engaging the outer surface of said wall, and a rim having an outer surface immediately adjacent the edges of said opening, said rim being formed with lugs thereon; clip means for holding said window means in place, each formed with wing means engaging the inner surface of said wall, other wing means connected to said first named wing means at an angle thereto and engaging the inner surface of said rim, said wing means being mutually formed to engage said lugs to hold said clip means in place thereon.

HENRY E. HINZ.

HENRY C. FLETCHER.
